(57) **CLAIM**

The ornamental design for a commode chair, as shown and described.

DESCRIPTION

FIG. 1 is a front and side perspective view of the commode chair, wherein the lid is closed, showing my design;

FIG. 2 is a front and side perspective view thereof, wherein the lid is open;

FIG. 3 is a side view thereof, an opposite side view being a mirror image thereof;

FIG. 4 is a front view thereof;

FIG. 5 is a rear perspective view thereof, wherein the lid is open;

FIG. 6 is a bottom perspective view thereof;

FIG. 7 is a front, exploded view thereof, showing the various components of the commode chair;

FIG. 8 is a top plan view thereof; and,

FIG. 9 is a bottom plan view thereof.
